FASTENER DEVICE FOR GARMENTS
AND THE LIKEJohann Fröhlich, Gotzis, Austria, assignor to
Henriette Mueller, Imguetli, Thal, Switzerland

Application May 6, 1949, Serial No. 93,368

13 Claims. (Cl. 2—42)

1
Garments intended for surrounding parts of the body, for example, bust and hip supports, sanitary towel supports, bodices, stays, corsets, corselettes, chemisettes, suspender belts, waistbands, maternity clothes, but also outer garments such as evening clothes fitting closely to the body, and furthermore bathing costumes, etc. have hitherto been made completely closed or even open.

The closed construction necessitates yieldable materials such as stockinet or knitted wear, in which the stitched binding is replaced by a woven union if elastic and yieldable threads such as rubber threads, artificial threads or the like are not interwoven. The tube-shaped closed structures, with or without sharing, have disadvantages, because they constantly press on the enclosed part of the body, impede the access of air, prevent the evaporation of body perspiration and, in the long run, become unattractive, burdensome, injurious to health and uneesthetic.

Consequently, the open construction of these structures is preferred today, but there are still no satisfactory means of closing them. If buttons cooperating with holes or loops are used, the buttons are forced through the outer garments so that they become visible. In addition, holes and loops do not, or only inadequately, withstand the strong forces which are to be expected. Moreover, the structures are put out of shape by these strong tensile forces, fold concertina fashion and finally form a cord or rope-like roll or bulge.

Efforts have already been made to overcome these difficulties by stretching the edges of the garments at the point of closure to form bands, these being joined after criss-crossing by a loop or bow. With this arrangement, however, the forces appear concentrated in the direction of the bands, so that the disadvantages set out above also arise.

Starting from the statement of object as thus defined, garments which are intended for surrounding or enclosing parts of the body and which are open when not in use are characterised, according to the present invention, by the arrangement of connecting members stiffening the edges of the garment at the point of closure by longitudinal stretching beyond them, those limbs of the connecting members which effect the edge stiffening being rigidly connected with one another in the adjusted position and, with a construction which is flat substantially parallel to the defining surface of the body, despite the insignificant thickness in the direction perpendicu-

lar to the defining surface of the body, being so defined in width that the moment of resistance of the limbs and their connection, which moment takes effect in the connecting plane of the edges, is sufficient to take up the forces occurring with normal wear of the garment without any lasting change in the shape of the connecting pieces transversely of the plane of stressing.

The advantages of this connection are obvious. Because of the stiffening of the edges at the point of closure, the forces coming into being are distributed absolutely uniformly over the length of the stiffening, that is, in practice, throughout the edge at the point of closure, since the extent of the stiffening or reinforcing will be made as long as possible. In practice, therefore, there is exerted on the material of the garment, a pulling force which is distributed uniformly over its entire edge width, so that the formation of ridges, beads and rolls is avoided and moreover the garment does not go out of shape or form into concertina-like folds. The garment retains without modification the shape given to it at its point of closure, even when it has been worn for a very long time. However, by virtue of the flat formation of the connecting members, the result is achieved that the latter need only take up a fraction of the thickness of the material from which the garment is normally made.

In this way, the connecting piece is practically completely invisible, for it is of such small size that the thickness of the connection member is compensated for by other means such as compression of the material of the garment, which may be achieved by sewing together and, moreover, by the coincidence of reinforcing limbs and force-transmitting elements in the formation of a common member, the desired simplification is obtained. It is also possible to provide the reinforcements alongside separate force-transmitting elements. Despite the possibility of making the connection members surprisingly flat, it is possible, by corresponding width measurements in the direction perpendicular to the thickness extension, to produce easily the moment of resistance which is essential for taking up the forces without lasting change in shape of the connection members, since the forces become operative most favourably on the high edge profile of the connecting members. Elastic changes in shape are nevertheless, desirable, since they result in the connection members and the garment edges stiffened thereby at the point of closure pressing parallel to the body-defining surface or bear-

ing directly on said surface, so that the dimensioning of the connection members is clearly determined from these necessities and expedients.

All kind of means may be used to fulfil the requirement that the reinforcing limbs be connected with one another. A U-shape formation for the connection members is especially simple, but they may, however, also be made H, X, Y, A or V-shaped.

There exist two fundamental possibilities as regards the arrangement of the connection members, in that they may either remain permanently connected with the one edge or margin of the garment, except for laundry purposes, or they may be completely separable from said edge so that they are independent parts. In the first case, the connection members are expediently fixedly connected with the garment through one of the reinforcing limbs on the edge of the garment which is associated with and stiffened by said limb. This connection may be brought about in many ways. For example, the connection members may be sewn on the garment by one of the limbs, or the limbs may be sewn in, or it is also possible for them to be interwoven, etc. In the latter case, the connection members remain firmly attached to the garment even during washing, whereas in other cases they may be taken off and re-sewn on to the material after the latter has been washed. When artificial fabrics are used as materials for making the garment or portions thereof, it is possible for the connection members to be stuck, pressed, riveted, soldered or welded in or on to other known types of fixing means.

If the connection members are not constructed as independent parts i. e. are already firmly secured to the garment before the latter is finished ready for use, then the free reinforcing limb must serve for the fixing on the opposite edge of the garment at the point of closure. This is effected by a recess for accommodating the reinforcing limb, being associated with the latter on the opposite edge. However, if the connection or attachment members are made as independent parts, then such recesses for all free reinforcing limbs are provided in both edges or margins of the garment, provided they define or form a point of closure. The most simple construction of such recesses is characterised by a slit-like formation, although it is obvious that other forms of accommodation pockets are possible which are adapted to the actual shape of the reinforcing limbs, these not being restricted to a strip-like shape, since they may be undulatory, bent, spiral-shaped, arcuate, oval, elliptical or the like.

Moreover, as regards the formation of the recesses intended for the reception of the attachment members, there are a series of possible constructions which are to be explained in detail in conjunction with the drawing.

The present invention is based on the further recognition that no relationship exists between the shaping and girth of the part of the body enclosed. This condition can easily be provided for by individual production of the garments in question, but hitherto there did not exist any possible way of adapting mass-produced garments to actual requirement. This was particularly apparent with brassières, although the same conditions also obtain with other garments under consideration. As regards brassières, for example, large busts very often go with slender figures and, vice versa, the bust may often be small on a large figure. The discrepancies thus

arising between the construction of the breast pockets and the measurement of the brassières could not be adequately set even with a large range of articles, quite apart from the fact that smaller concerns, due to the purchase prices, changes in fashion, deterioration of the silk, and other circumstances which arise to increase the range almost to infinity, are simply not in a position to keep brassières in stock in the necessary sizes according to size of breast pockets, construction and measurement, to which must also be added further modifications according to style, colour, fastenings, positions of fastenings, etc.

15 Arising from this recognition, it is further proposed according to the invention to construct the garment of a main portion which is adapted to the shape of the part of the body enclosed or which enforces a predetermined shape for soft parts of the body, and of one or more additional insert portions, the lengths of which are to be made different in conformity with the actual measurements of the covered part of the body. It is only necessary to choose a main portion of 20 a size to conform to the given or desired shape of the bust, when it is a question of a brassière. Thereupon, subsequent to this selection, made without any regards to the body measurement, the insert portion is ascertained which will fit 25 the brassière to such measurement. There are also cases in which the anatomical position and formation of the stomach is such that, after taking meals, the brassière previously worn resulted in pains or becomes so tight that no fastening would hold. In this event, by selecting 30 a longer insert piece, it is possible with little manipulation to carry out the necessary adaption without fear of difficulty or of the brassière falling off completely.

35 This proposal, which possesses independent inventive importance, depends however to a great extent on the construction and completeness of the fastening means, i. e. the connection between the main and insert portions. It is true 40 that the insert portions, which are preferably highly elastic, but which may also be non-elastic, can be joined to the main portion by buttons, 45 hooks, strips or sliding clasp fastenings, but the nature of the connection influences the general seating of the main portion, so, that its exact 50 fitting loses its meaning if such fitting is impaired or destroyed by bulging and concertina-like formations between the main portion and the insert portions, especially as these changes 55 in shape are passed on to the main portion and cause changes in its position and shape. Consequently, this idea is only made effective in a fully satisfactory manner by the use or arrangement of attachment members reinforcing the 60 edges of the garment at the point of closure between the main portion and insert portions by longitudinal extension over them, those limbs of the attachment members which effect the edge stiffening being rigidly connected with one 65 another in the adjusted position and, with a construction which is flat substantially parallel to the defining surface of the body, despite the insignificant thickness in the direction perpendicular to the defining surface of the body, being so 70 defined in width that the moment of resistance of the limbs and their connection, which moment takes effect in the connecting plane of the edges, is sufficient to take up the forces occurring with normal wear of the garment without 75 any lasting change in the shape of the connec-

5

ting pieces transversely of the plane of stressing. The drawing shows one embodiment of the invention as applied, for example, to a brassière, and shows further possibilities of applying the invention, for example, to evening dresses.

Fig. 1 shows a view of the back of a person wearing a brassière constructed in accordance with Fig. 2.

Fig. 2 shows the brassière embodying the invention, this figure illustrating the closure or fastening means and the insert piece in elevation and to an enlarged scale;

Fig. 3 shows a section through the brassière and the fastening means on the line III—III of Fig. 2, to a distorted scale in which the thickness is enlarged relative to the length;

Fig. 4 represents a somewhat modified construction of the connection or attachment members;

Fig. 5 shows an elevation of the fastening of an evening dress with the connection members proposed in accordance with the invention, the fastening being effected on the back of the dress;

Fig. 6 shows a fastening at the side;

Fig. 7 shows a section of the back portion of a brassière in which the connection member is held by a closure which is secured by resilient construction of the stiffening receiving one limb of the connection member;

Fig. 8 shows a side elevation of the connection member serving for this purpose;

Fig. 9 is a plan view of the point of closure according to Fig. 7 and to a larger scale; and

Fig. 10 finally shows a side elevation of the reinforcement or stiffening, seen in the direction of the line X—X of Fig. 9.

As shown in the drawing, the brassière according to Figs. 1-3 consists of a main portion which is accurately fitted to the shape of the bust or which enforces a predetermined shape thereof, the ends of said main portion extending on to the back to the wearer and being visible at 1 and 2. This main portion may be made to any suitable shape and in accordance with all existing knowledge; it does not form the subject of the present invention, but it is of importance only in so far as it provides the means whereby the function allotted to it of supporting and shaping the bust is completely fulfilled as far as possible, by its actual shape, without any attention having to be paid to the bust measure of the wearer. However, it is simplified in accordance with the invention by an insert portion 3, which may be made in different lengths according to the bust measurement of the wearer, i. e. with the actual girth of the part of the body to be surrounded. In the example shown, the insert piece 3 consists of a short length of rubber band. In place of the rubber band, there may however also be employed all other possible constructions which may include non-elastic bands. Moreover, it is not necessary to use a single insert piece, as several such pieces may be employed. For example, non-elastic bands are used if the main portion itself is made of elastic material or includes elastic portions, as is often the case with hip girdles or "roll-ons" in order that the abdomen may be pulled in.

In further developing the invention, the edges 4, 5 of the main portion ends 1, 2 forming the point of closure or fastening are stiffened by the connection or attachment members, one of the two limbs 6 of this connection member, which is of U-shape, being accommodated in the associated edge 4 or margin 4 or 5 of the garment.

6

In the example illustrated, this is effected by the fact that the pockets or slots 13 and 14 are formed by the stitching 7 and 8 extending across the full width of the ends 1 and 2, by the stitchings 9 and 10 which do not extend across the full width of said ends, and finally by the transverse stitchings 11 and 12, the limbs 6 being accommodated in said pockets or slots. Due to the stitchings 9 and 10 not extending across the full width of the ends 1 and 2, an insertion opening 15 or 16 is thus formed through which the connection member may be introduced into or removed from the pockets or slots 13 and 14 in the ends 1 and 2, respectively. Naturally, this is only possible if the ends 1 and 2 have a double-wall construction at this point, and this can be done in many ways. In the example illustrated, the double-wall effect is obtained by the material 17 of the main portion of the brassière (see Fig. 3) being doubled at the parts forming the ends 1 and 2 by the fabric stiffenings 18. By means of the stitchings 10 and 8 already mentioned, and further by means of the longitudinal stitchings 19 and the transverse edge stitchings 20 and 21, the reinforcements 18 are firmly connected or stitched to the material 17 forming the main portion of the brassière. With this arrangement, the stitchings 10, 8, 19, 21, 20 and 12 so compress the thickness of the material 17 in the region of the reinforcements 18 that despite the arrangement of the reinforcements 18 and despite the reception of the limbs 6 of the connection members, the thickness of the material in the region of the end 2 of the main portion does not exceed the thickness of the brassière main portion in the remaining portions. What has been illustrated for the end 2 in the right-hand half of Fig. 3 also applies to the left end 1 of the brassière, this latter end not being shown in cross-section.

In order now to bring about the connection with the insert-piece 3, the following further devices are provided.

The tension strap member 3, which is inlaid with rubber threads (see the left-hand side of Fig. 3) is likewise set in reinforcement which, differing from the fabric reinforcement 18, consists of rigid material such as, for example, light metal, rustless metal sheets or sleeves. In cross-section, these metal mounts are of U-shape, as shown on the left in Fig. 3. Disposed between the free limbs 22 and 23 of the metal mounts 24 are the ends 24' and 25' of the tension strap member 3 which are associated with the ends 1 and 2 of the main portion of the brassière. The limbs 22 and 23 are connected together by rivets 26 which so compress the ends 24' and 25' that the thickness of the material 17 in combination with that of the edge selvage 27, or the thickness of the parts 17 and 18 including that of edge selvage 27, is not exceeded in the region of the reinforcement 18. Also formed in the mounts are slot-like recesses 28 which are open at the upper ends and lower ends so that the second limb 29 of the connection member (not previously mentioned) can be accommodated in the mounts 24. The passing of the limbs 29 into the slots 28 thus produces a firm connection, the limbs 29 being firmly held in the mounts 24 by sliding them into the slots, which taper slightly in a downward direction (not shown). Allowance is made for the width of the connecting limb 31 of the connection members 3, 28, 34 by means of a recessed portion 33 on each mount 24. Moreover, the transverse seams or stitchings 11 and 12 prevent the limbs

6 from slipping downwardly in the recesses 13 and 14.

It is apparent from Fig. 3 that the connection members 6, 29, 31 stiffen the edges 4 and 5 of the garment at the point of closure, formed by the ends 1 and 2 of the open-ended main portion of the brassière, by longitudinal extension beyond the height of these edges, that the limbs 6 which effect the edge stiffening and the limbs 29 stiffening the edges 24', 25' of the insert pieces 3 are rigidly connected to one another in the adjusted position by the middle or connecting limb 31, and that with a construction that is substantially flat relatively to the body defining surface, in spite of being of insignificant thickness in the direction perpendicular to the body defining surface, the breadth of the limbs of the connection members is such that the moment of resistance of the limbs 6, 29, 31 arising in the plane of connection of the edges 4 and 5, or 24' and 25', respectively, is adequate in order to take up the forces normally occurring during wear of the brassière without deformation of the connection pieces 6, 29, 31 transversely to the plane of stress. It will be recognised that there are wide limits within which the breadth dimensions of the limbs 6, 29, 31 may fall. When the connection members are made of metal, experience has shown that a limb breadth of 4 to 6 mm. is quite adequate, whereas the thickness may be from 1 to 2 mm. This thickness lies within the elastic yieldability of layers of material in the sewing, so that the proposed connection causes practically no wear on the garments. When speaking of changes in shape of the connection members herein, it is understood that substantially permanent alterations in shape are meant; elastic distortions which serve to cause the connection members to press on the body surface are desirable.

The embodiment illustrated therefore shows connection members which are formed in such manner that, when the garment is not in the form in which it is worn, they are completely separable from the garment and are thus parts having a certain independence which are not permanently attached thereto. This arrangement has the advantage that non-textiles can be completely separated from the textiles, which is desirable but not absolutely essential for washing purposes. It is also possible to replace the mounts 24 by arrangements in accordance with the right half of Fig. 3. Moreover, it is not necessary for the connection illustrated to be provided at both sides of the insert piece 3. The tension or elastic strap 3 can be sewn on to one side or be connected in any suitable manner with the associated end portion. In this case, however, the advantage of being able to change the insert piece 3 at any time is lost to a certain extent.

By foregoing the advantage of being able to separate the connection members completely from the garments, one of the two limbs of the connection member can remain permanently connected with the garment, e. g. it may be sewn to it. All these modifications come within the scope of the invention, and no departure from this exists if one of the advantages that can be obtained is given up in favour of a corresponding simplification of the construction or arrangement.

The fitting of the brassière, made in accordance with Figs. 1 to 3 is very simple. After selecting the main portion in accordance with the best possible support and shaping of the bust, and after selecting the insert portion or portions 3 in accordance with the bust measurement, the bras-

sière is fitted in such a manner that with the connection members inserted in the pockets 13 and 14, the ends 1 and 2 lie on the front of the body. The free limbs 29 are now inserted into the slot 28 of the mount or the elastic strap 3 is slid over the limb 29. The brassière is then twisted by light tensioning of the strap 3 until the breast pocket or bags accommodate the breasts. Thereupon, the straps or supports 32, 33 (Fig. 1) are stretched over the shoulders.

Fig. 4 shows a somewhat modified form of the mounts 24 and the connection members 6, 29, 31 for women with very big busts or women who, because of household duties, occupations requiring great activity of the body and heavy movement, or participation in certain kinds of sports, etc., cause especial strain to be placed on the brassière so that the frictional coupling of the limbs 6 and 29 is no longer sufficient to hold them in their pockets or slots. The friction coupling could be strengthened by spring means. For example, this could be achieved by the slot 28 at the left of Fig. 3, being extended all the way towards the right and the free tongues thus formed being bent over, so that the ends of the tongues bear against one another when the limb 29 is not inserted. Upon introducing the limb 29, a counteracting spring effect is produced by the spreading of the tongue ends in such a manner that the limb is held even against increased forces. Moreover, spring-mounted balls could also be arranged in the solid part above the slot 28, such balls springing into a ball-socket arranged in the limb 29. In a simplified construction, it is sufficient to form a ball-like projection on one of the tongues resulting from the slitting up of the part 24, the convex projection engaging in a concave recess in the limb 29. Obviously, the kinematic reverse of this arrangement is also possible. An even stronger securing means is naturally obtained by a positive connection which may be achieved in a very simple manner as shown in Fig. 4. For this purpose, the limb 29 has a hook-like projection at 34 and the breadth of the slot 28 is chosen such that the limb can be inserted into the slot 28 of the mount 24 from below, despite this projection. In addition, the mount 24 has a recessed portion at 35. The hook projection 34 springs out of this under the effect of the constantly prevailing tension directly the limb 29 has been passed through the slot 28, and thus the attachment is positively secured. If necessary, for cutting out the tension causing the positive fastening, a supplementary piece may be introduced between the limb 29 and the right hand slot-defining wall. In order to be able to secure the limb 6 with the same certainty in the pocket 13, it is sewn at 36. Since this can be done with a few stitches, the breaking thereof before washing and the re-stitching after washing presents no difficulties.

Fig. 5 shows the use of the novel connection members as a back fastening of an evening dress. Provided on the neckband 37 are connection members 6, 29, 31 having limbs of equal length and adapted to be accommodated at both sides in material pockets of the type shown at 13 and 14. The marginal portions of the dress may obviously also be provided at the point of closure with mounts of the type shown at 24, perhaps of synthetic substances of a certain yieldable nature and of a colouring to match the colours of the material. At 38, the middle or connecting limb 31 bridges over a slot 39 provided for baring the back of the wearer. In this case, the bared

connecting limb may constitute an ornamentation by making it of precious metals and studing it with jewels, or it may be made as other forms of decoration.

Fig. 6 shows the employment of the connection members in a side fastening. In a similar manner, bathing suits, sportswear and the like may be so equipped. There is no necessity for it to be restricted in any way to ladies' clothing and garments, since the invention may be used on menswear and boyswear. This applies especially to bathing suits, sunbathing suits, sportswear, vests, close-fitting clothing such as fencing suits, dancing frocks and costumes, theatre costumes and the like.

In the constructional example according to Figs. 7-10, the right-hand limb 6 of the connection members is sewn, by means of holes 36 arranged therein, to the section 2 of the rear part of the brassière, the stitching being shown at 40. For this purpose, a pocket 41 is formed in the section 2 by means of the stitching 42. As in the example according Fig. 4, the other limb 29 has a hook-like projection 34 and the limbs 6 and 29 are interconnected by the portion 31. As compared with the example according to Fig. 4, however, it shows the difference that the hook-shaped projection 34 is not accommodated in a recessed portion 35 of the mount 24, but the mount 24, which is U-shape in cross-section, is formed at 43 with a hole-like recess into which the hook 34 fits as soon as the brassière is closed by introducing the limb 29 into the slot 28 of the mount 24. The latter is formed at 44 with pressed-out tongues which are directed towards one another and which penetrate into the insert portion 3, as shown in Fig. 9, and thereby firmly connect the insert portion 3 to the mount or reinforcing member 24. In order that the hook 34 will remain with certainty in the hole 43 when the brassière is fitted and will not be pulled out of the hole 43 under action of strong tensile force components, the mount 24 is no longer made closed at the lower end, as shown in Figs. 2 and 3, but is open at this point. The free lugs 24' and 24'' thus formed are brought towards one another in such manner, that their distance apart, in the undeformed state, is smaller than the thickness of the central portion 31 (see Fig. 10). By these means, the springy lugs 24' hold the connection member, after the limb 29 has been inserted in the slot 28, in a position in which the hook 34 remains in the hole 43. This prevents the brassière, when once fastened, from being accidentally unfastened again.

The examples illustrated in no way exhaust the possibilities of the invention, which may be carried into effect in many different ways.

What I claim is:

1. A fastener device for detachably securing together two adjacent edges of fabric material disposed in approximately abutting relation, and comprising, in combination, a relatively rigid mount secured to one of the fabric edges, a closure member connected to the other fabric edge and having a part cooperating with said mount to interlock with the same, said mount being provided with a longitudinal slot for receiving the aforesaid part of the closure member, and resilient extensions on the mount at one end of the slot and spaced apart a distance smaller than the transverse width of the slot, said resilient extensions being adapted to be forced apart as the said part of the closure member is inserted into the slot and to return to their original posi-

tion when the said closure member part is in final position in the slot, whereupon said extensions resist disengagement of the closure member from the mount.

5 2. A brassière comprising a main body portion having oppositely disposed edges for securement to each other, an insert piece having opposite edges between the aforementioned edges, and fastener devices connecting each of the edges of the insert with an adjacent edge of the brassière, each of said devices comprising a mount of U-shaped cross-section receiving one of the adjacent insert piece and brassière edges between the walls thereof and secured thereto, said edge being spaced from the forward, unsecured edge of

10 the mount to provide a longitudinally extending slot, a U-shaped hook member of sheet metal comprising two substantially parallel legs and a connecting bridge member, the hook member being secured to the other of the adjacent insert piece and brassière edges by one of its legs, the other leg thereof being constructed to be inserted in the said slot of the mount for interlocking the latter with the hook member.

15 3. A brassière as defined in claim 2 wherein the forward, unsecured edge of the mount is provided with a recess at one end thereof communicating with the slot, said recess being adapted to receive the bridge member and being of such a height that the upper edges of the bridge member and mount are substantially flush with each other.

20 4. A fastener device for detachably securing together two adjacent edges of fabric material disposed in approximately abutting relation, and comprising, in combination, a relatively rigid mount of approximately U-shaped transverse cross-section and receiving between its ends one of the fabric edges and secured to such fabric edge, and a hook member of U-shaped form adapted to be connected by one leg to the other fabric edge, said mount having a slot therein for receiving the other leg of said hook member for interlocking therewith, the unsupported edge of the mount being parallel to the edge of the fabric material secured thereto and being provided with a recess at one end thereof connected with the slot interiorly thereof, said slot being parallel to the unsecured edge of the mount, said recess being adapted to receive the leg of the hook member for guidance into said slot and being of such height that the ends of the mount and hook member are substantially flush with each other.

25 5. A fastener device for detachably securing together two adjacent edges of fabric material disposed in approximately abutting relation, and comprising, in combination, a relatively rigid mount of approximately U-shaped transverse

30 cross-section and receiving between its ends one of the fabric edges and secured to such fabric edge, a hook member of U-shaped form adapted to be connected by one leg to the other fabric edge, said mount having a slot therein for receiving the other leg of said hook member for interlocking therewith, and a projection and a recess disposed on the interlocking mount and hook member leg adapted to secure such leg to the mount, the projection being disposed on the hook member leg and extending in the direction of the other leg substantially in the plane of the hook member, and the recess being located in the unsecured edge of the mount.

35 6. A fastener device for detachably securing together two adjacent edges of fabric material

disposed in approximately abutting relation, and comprising, in combination, a relatively rigid mount of approximately U-shaped transverse cross section and receiving between its ends one of the fabric edges and secured to such fabric edge, and a hook member of U-shaped form adapted to be connected by one leg to the other fabric edge, said mount having a slot therein for receiving the other leg of said hook member for interlocking therewith, the unsecured edge of the mount being provided with a recess at one end thereof communicating with the slot for introducing the said other leg of the hook member into such slot, at an angle thereto, the upper portion of such other leg being of tapered form.

7. A brassière as defined in claim 2, wherein the leg received within the slot is provided with a lateral projection adjacent to the free end thereof remote from the bridge member and wherein the forward unsecured edge of the mount is provided with a recess arranged to receive said projection for holding the hook member against accidental release from the mount.

8. A brassière as defined in claim 7, wherein the ends of the mount adjacent to said recess are bent toward each other and are adapted to be spread apart as the said leg is inserted into said slot, said ends returning to their original position when such leg is in final position in the slot and acting to restrain disengagement of the hook member from the mount.

9. A fastener device for detachably securing together two adjacent edges of a garment made of fabric material and disposed in approximately abutting relation and comprising, in combination, a hook member of flat, knife-blade form and of U-shape, one leg of the hook member being adapted to be anchored in a loop of the fabric material at one edge of the garment so as to be covered with fabric on the surface facing the body of the wearer, and an eye-like mount of U-shape in transverse cross-section and adapted to receive between its limbs the other edge of the garment, such garment edge and the central bend of the U-shaped mount being spaced from

5

10

15

20

25

30

35

40

45

each other to provide a longitudinal slot which is closed along its longitudinal edges, the free leg of the hook member being received in said slot.

10. A fastener device as defined in claim 9, wherein the fabric edge received between the limbs of the mount is compressed therebetween to such an extent that the total thickness of the mount with the fabric between its limbs is equal to the thickness of the free fabric, so that the outer surface of the limbs is flush with the outer surface of the free fabric.

11. A fastener device as defined in claim 9, wherein the central bend of the U-shaped mount is provided with a recess at its lower end into which the central portion of the U-shaped hook member locks when the free leg of the latter is received in the said slot.

12. A fastener device as defined in claim 9, wherein the free leg of the hook member is provided near its outer end with a projection extending toward the anchored leg in the plane of such member, the central bend of the mount having a recess for receiving said projection in the interlocked condition of the hook member and mount.

13. A fastener device as defined in claim 9, wherein the hook member and mount are formed entirely of sheet metal, and are constructed and mounted on the garment symmetrically with respect to a median plane, whereby tension is transmitted continuously along and symmetrically with respect to the central plane of the fabric and distortion of the garment outline is avoided.

JOHANN FRÖHLICH.
